US0D1094326S

(12) **United States Design Patent** (10) **Patent No.:** **US D1,094,326 S**
Liu et al. (45) **Date of Patent:** **** Sep. 23, 2025**

(54) **HOLOGRAPHIC DISPLAY CONTAINER**

(71) Applicant: **SHENZHEN BEIHAI RALL TRANSIT CENTURY TECHNOLOGY CO., LTD.,**
 Guangdong (CN)

(72) Inventors: **Hongde Liu**, Shenzhen (CN); **Qing Chen**, Shenzhen (CN); **Ying Chen**, Shenzhen (CN)

(73) Assignee: **SHENZHEN BEIHAI RALL TRANSIT CENTURY TECHNOLOGY CO., LTD.**, Shenzhen (CN)

(**) Term: **15 Years**

(21) Appl. No.: **29/880,085**

(22) Filed: **Jul. 18, 2023**

(51) **LOC (15) Cl. 14-03**

(52) **U.S. Cl.**

USPC **D14/496**

(58) **Field of Classification Search**

(57) **CLAIM**

The ornamental design for a holographic display container, as shown and described.

DESCRIPTION

FIG. 1 is a front and top perspective view of the holographic display container, showing our new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures illustrate portions of the holographic display container that form no part of the claimed design.

1 Claim, 8 Drawing Sheets
